RAIL ANCHOR

Charles G. Ericson, Toronto, Ontario, Canada

Application November 22, 1940, Serial No. 366,535
In Canada November 9, 1940

8 Claims. (Cl. 238—324)

This application is a continuation-in-part of my copending application, Serial No. 336,109, filed May 20, 1940, for Rail anchors.

Since obtaining my prior patents numbered 1,402,852, 1,548,589, and 1,996,286, issued January 10, 1922, August 4, 1925, and April 2, 1935, respectively, it has become increasingly apparent that rail anchors must not only function to prevent creepage of the rails but must prevent, or at least minimize, danger of damage to the rails by derailed wheels. During the past few years rapid advancement has been made in rails and roadbeds and in every kind of railway rolling stock to increase the speed of traffic of every description. Accidental wheel derailments at such high speed have caused the flanges of the rails to be severely damaged by the wheels striking certain parts of the rail anchors shown in my prior above-mentioned patents. The object of my present invention is to provide a simple anchor of the type shown in my above-mentioned copending application but which has been improved in certain respects to reduce the cost of manufacture and to reduce the possibility of danger of damage to the rail by derailed wheels striking anchor parts.

The features of the invention are hereinafter described in connection with the accompanying drawings in which

Fig. 1 is a perspective view of my rail anchor in service position on a rail base;

Fig. 2 is a cross section of part of the rail showing the yoke in its initial position on a shoe;

Fig. 3 is a horizontal section of the rail showing in plan the parts shown in Fig. 2;

Fig. 4 a cross section of part of the rail showing the yoke in a service position on the shoe;

Fig. 5 a horizontal section of the rail showing in plan the parts shown in Fig. 4;

Fig. 6 a plan view of the underside of the shoe;

Fig. 7 a perspective view of the shoe;

Fig. 8 an end view of the short hook;

Fig. 9 a view showing the hooked end of the yoke disengaged from the rail base by a derailed wheel;

Fig. 10 a view showing the upstanding portion of the yoke disengaged from the shoe by a derailed wheel;

Fig. 11 a cross sectional detail through the shoe showing the yoke engaged therewith in its operative position; and

Fig. 12 a detail in plan of part of a shoe and yoke showing a modified form of the shoe engaging portion of the yoke.

In the drawings like numerals of reference in-

dicate corresponding parts in the different figures.

The rail anchor is shown as applied to a rail of the conventional type having the usual head portion 1, intermediate web 2 and base 3. The rail base has the lower flat face 4, the vertical side edges 5, and the upper sloping face 6, and the rail is shown as resting upon the stationary tie 7.

10 The rail anchor as shown comprises a shoe adapted to fit and embrace an edge portion of the rail base and a yoke adapted to span the rail base and engage one edge of the rail base and embrace the shoe to lock the parts in place upon the rail.

15 The shoe as constructed in accordance with the present invention comprises an elongated member having a slot formed longitudinally thereof to receive the rail edge, and this slot is formed with a non-continuous upper jaw comprising two lugs 8, 8^a, and a non-continuous lower jaw comprising two lugs 9, 9^a. The lower jaws or lugs 9, 9^a are located at opposite ends of the shoe and have an open space 9^b between them. 20 The upper jaws or lugs 8, 8^a are also located at the opposite ends of the shoe and have a cut-away portion 8^b separating them. The slot has an upstanding rear wall 10 which increases in thickness from the outer end of the shoe towards the tie engaging end thereof. Thus the back 10^a of the shoe is inclined longitudinally inwardly from the tie engaging end of the shoe to the outer end thereof. The said back has a plane surface which, in addition to the above-mentioned longitudinal inclination, is also inclined 25 inwardly transversely of the shoe from the lower edge to the upper edge of said back. The plane surface of the back 10^a is therefore inclined in two directions, longitudinally and transversely.

30 The upstanding rear wall 10 is provided intermediate its ends with a recess 11 to ensure positive contact at both ends against the vertical edge 5 of the rail base. The lower jaws or lugs 9, 9^a engage the lower face 4 of the rail base in intimate contact and the intermediate open space 9^b permits free movement of the rail undulations under the impact of the traffic load and the cut-away portion 8^b between the upper jaws 8, 8^a provides additional clearance under conditions of extreme traffic undulations. While the lower jaws 9, 9^a are in parallel contact with the underface 4 of the rail base, the upper jaws 8, 8^a incline at a different angle than that of the upper sloping surface 6 of the rail base to the extent that the

Fig. 11 a cross sectional detail through the shoe showing the yoke engaged therewith in its operative position; and

Fig. 12 a detail in plan of part of a shoe and yoke showing a modified form of the shoe engaging portion of the yoke.

In the drawings like numerals of reference in-

outer terminals of the jaws 8, 8^a and 9, 9^a are closer together than the rail thickness to provide a pinching engagement between the jaws and the rail base when the shoe is forced into position thereon.

The tie engaging end of the shoe is provided with a downwardly extending abutment 14 having a broad tie engaging surface 15, a reinforcing flange 16, and a stiffening rib 17.

Having described the construction of the shoe of the present invention, the yoke of the present invention that cooperates therewith as the clamping member will now be described.

The yoke comprises a resilient body portion 18 adapted to extend under and span the rail base 3. This body portion is provided at one end with an upwardly extending short hook 19 of which the upstanding portion 20 engages the vertical edge 5 of the rail base flange and the inwardly extending portion 21 engages, in overhanging relation, the upper sloping surface 6 of the rail base only adjacent the edge 5 thereof. This inwardly extending portion 21 of the short hook end is formed as a lip having a depth less than the depth or thickness of the portion of the rail base underlying the lip so that the mass of metal in the rail base immediately beneath the lip is greater than the mass of metal in the lip. The upper surface 23 of the lip 21 is upwardly and outwardly inclined whereby if a rapidly revolving derailed car wheel or the like engages the said inclined surface 23 the lip will be forced from the upper sloping surface 6 into engagement with the vertical edge 5 as shown in Fig. 9 or the lip will be damaged. In either case the rail base will not be damaged because the lip will be broken off before it could be forced through the rail base.

The upstanding portion 20 of the hook end 19 is upset in the forging operation and its cross sectional area is increased so that, when this end is forced into tension transversely in relation to the upwardly extending portion on the opposite end of the yoke the reinforced upstanding portion 20 is capable of withstanding the tensional stresses imposed during the application process and as may occur under the creepage load and thus minimize the tension stresses in the overhanging lip 21.

It will be noted that not only is the width, at the points 35, of the upstanding portion 20 greater than the width of the bar from which the yoke is made but the thickness of the portion 20 is also greater than that of the said bar. The cross sectional area of the portion 20 is thus greater than that of the said bar. The increased width of the portion 20 is continued upwardly so that the lip 21 is also wider than said bar whereby the cross sectional area of the lip in a horizontal plane is greater than the cross sectional area of the bar. The depth or thickness of the lip is considerably less than that of the bar whereby the cross sectional area of the lip in a vertical plane is less than the cross sectional area of the bar. By making the lip 21 thin and increasing the ruggedness of the upstanding portion, I provide the least possible obstruction to a derailed wheel without sacrificing the strength of the hook where it is needed to withstand the above mentioned stresses.

The opposite end of the body portion 18 has an upwardly extending portion 27 adapted to engage the back 10^a of the shoe. Between the portion 27 and the body portion 18 which underlies the rail base is a downwardly extending portion 32 which clears the underside of the lower jaws 9,

9^a. The upwardly extending portion 27 is inclined to a vertical plane in a direction corresponding to the transverse inclination of the shoe back 10^a but at a different angle than that of said transverse inclination of the shoe back so that initially only the upper part or edge of the portion 27 will engage the upper part or edge of the back 10^a. The distance from the innermost edge of the upwardly extending portion 27 to the inner surface of the upstanding portion 20 of the hook end, is such, relative to the width of the rail base 3 plus the thickness of the entering or outer end of the longitudinally inclined portion 10^a of the shoe, that the steel yoke may readily be placed in its starting position on the rail base and the shoe. The back of the latter is tapered or chamfered at 33 to facilitate this without unduly increasing the length of the shoe. That is to say, the back 10^a is inclined longitudinally inwardly towards the yoke entering end of the shoe and is then tapered in the same direction but more sharply at said entering end whereby the back has a double inclination longitudinally thereof. As the yoke is forcibly moved along the rail base from the short inclined or tapered end 33 to its operative or service position on the comparatively longer longitudinally inclined part of the double inclination on the shoe back 10^a, the upper end of the upwardly extending portion 27 will be forced outwardly away from the upstanding portion 20 of the hook end of the yoke and thus the underlying body portion 18 of the yoke will be sprung upwardly against the lower face of the rail base 3 which results in the upwardly extending portion 27 being drawn gradually towards parallelism with the transverse inclination of the shoe back 10^a to increase its gripping engagement therewith. In other words, only the upper part or edge of the yoke portion 27 engages the upper part or edge of the tapered or short inclined entering end 33 of the shoe back 10^a when the yoke is initially positioned on the shoe and subsequently the upper part of the portion 27 is drawn inwardly so that a greater area thereof will engage the shoe back when the yoke is moved to its operative or service position on the shoe. Any tendency of the portion 27 to loosen itself from the shoe is thus resisted. To avoid any possibility of lessening the tension between the upper part of said portion and the upper part of the shoe back which might result in the yoke becoming loose on the shoe, the parts are so designed that under ordinary circumstances the extreme lower part or edge of the back 10^a will not be intimately contacted by the portion 27. The upper end of the portion 27 terminates adjacent the upper edge of the shoe back 10^a so that the said portion does not overlie the upper jaws 8, 8^a of the shoe.

The upwardly extending portion 27 is initially twisted so that the shoe engaging face of said portion normally lies substantially parallel to the short longitudinal taper 33 of the shoe. The turned or twisted portion 27 facilitates the movement of the shoe engaging face of said portion 27 along the shoe back 10^a. During this movement the portion 27 is distorted to follow the contour of the other longitudinally inclined part of the shoe back 10^a, see Figs. 3 and 5. Thus not only is the upstanding portion 27 of the yoke tensionally drawn into firm engagement with the shoe, but it is so distorted that it exerts a biting engagement between said portion and the engaged inclined surface 10^a of the shoe to resist withdrawal of the yoke therefrom.

With this construction, no part of the upwardly extending portion 27 overlies the rail base. If a derailed wheel travelling at a high speed strikes the yoke portion 27 or the shoe, the latter may be broken or the portion 27 shifted as shown in Fig. 10 but in neither case will the flange of the rail base 3 be materially damaged.

Instead of initially twisting or turning the upwardly extending portion 27, the latter may be formed with a rounded leading edge 34 which will move along the inclined shoe back 10° without digging into the latter and will cause the portion 27 to be twisted or turned to resist withdrawal of the yoke from the shoe, see Fig. 12.

Preferably the shoe is made of malleable iron and the yoke of steel, the harder metal of the yoke will thus take a firm frictional grip on the softer metal of the shoe to hold these parts as positioned relative to one another and to the rail during extreme vibrations incident to traffic. There are six points of engagement between the shoe and the rail base, three points of engagement between the yoke and rail base (lip 21, upstanding portion 20 and body portion 18 which engages the underside of base), and one point of engagement between the yoke and shoe making a total of ten separated points of engagement. This ensures proper tensioning of the yoke to ensure the necessary frictional engagement between the yoke and the shoe and this engagement is further accentuated by the specific constructions of the anchor parts.

It will be seen from the foregoing that the rail anchor of the present invention may be readily applied to a rail by positioning the shoe on a rail, with its abutment surface 15 engaging a tie 7, and then engaging the yoke with the rail by hand so that the upwardly extending portion 27 engages the short tapered end 33 of the shoe as shown in Fig. 3. The operation is thereafter completed by driving the yoke portion 27 along the other longitudinally inclined part of the shoe back 10°, as shown in Fig. 5, until the desired clamping action is secured. The parts may be removed from the rail when desired by driving the yoke in the reverse direction.

What I claim as my invention is:

1. A rail anchor comprising a shoe formed of substantially unbendable material adapted to embrace one edge of a rail base and provided with a tie engaging end and a back having a plane surface inclined in two directions, first longitudinally inwardly from the tie engaging end of the shoe to the outer end thereof to form a longitudinal wedge portion inclined towards the edge of the rail base, and secondly transversely inwardly from the lower edge to the upper edge of said back; and a yoke of resilient metal adapted to span the rail base having a hook at one end adapted to engage the edge of the base remote from the shoe and having an upwardly extending portion at the other end adapted to engage the inclined back of the shoe, the said upwardly extending portion being inclined in a direction corresponding to the transverse inclination of the back of the shoe but at a different angle than that of the said transverse inclination so that initially only the upper part of the said upwardly extending portion will engage the upper edge of the said wedge portion thus as the yoke is moved along the shoe to a service position the upwardly extending portion will be drawn gradually inwardly to increase the area thereof in engagement with the wedge portion to ensure a firm gripping engagement between said up-

wardly extending portion and the back of the shoe.

2. A rail anchor comprising a shoe formed of substantially unbendable material adapted to embrace one edge of a rail base and provided with a tie engaging end and a back having a plane surface inclined in two directions, first longitudinally inwardly from the tie engaging end of the shoe to the outer end thereof to form a longitudinal wedge portion inclined towards the edge of the rail base and secondly transversely inwardly from the lower edge to the upper edge of said back; and a yoke of resilient metal adapted to span the rail base having a hook at one end adapted to engage the edge of the base remote from the shoe and having an upwardly extending portion at the other end adapted to engage the inclined back of the shoe, the said upwardly extending portion being inclined in a direction corresponding to the transverse inclination of the back of the shoe but at a different angle than that of the said transverse inclination, the said upwardly extending portion also being initially turned to correspond to the longitudinal inclination of said wedge portion but at a greater angle than that of the longitudinal inclination of said wedge portion so that initially only the rear upper part of said portion will engage the upper edge of said wedge portion thus establishing a firm gripping engagement between the said upwardly extending yoke portion and the wedge portion of the shoe by distortion of the said yoke portion as it is moved along the wedge portion to a service position.

3. A rail anchor comprising a shoe formed of substantially unbendable material adapted to embrace one end of a rail base and provided with a tie engaging end and a back having a plane surface inclined in two directions, first longitudinally inwardly from the tie engaging end of the shoe to the outer end thereof to form a longitudinal wedge portion inclined towards the edge of the rail base, and secondly transversely inwardly from the lower edge to the upper edge of the back, the said outer end of the wedge portion being tapered; and a yoke of resilient metal adapted to span the rail base having a hook at one end adapted to engage the edge of the rail base remote from the shoe and having an upwardly extending portion at the other end adapted to engage the inclined back of the shoe, the said upwardly extending portion being inclined in a direction corresponding to the transverse inclination of the back of the shoe but at a different angle than that of the said transverse inclination, the said upwardly extending portion also being initially turned so that its wedge engaging face will lie substantially parallel to the tapered end of the wedge portion so that initially only the rear upper part of said upwardly extending portion will engage the upper edge of the said wedge portion thus establishing a firm gripping engagement between the upwardly extending yoke portion and the wedge portion by distortion of the said yoke portion as the yoke is moved along the shoe to a service position.

4. A rail anchor comprising a shoe formed of substantially unbendable material having a longitudinal extending slot to embrace an edge of a rail base and formed between non-continuous lower jaws and non-continuous upper jaws, the slot having a substantially vertical wall for contacting the vertical edge of the rail base, the vertical wall having a slight recess formed intermediate its ends so that only the latter contact

the adjacent edge of the rail base, the back of the vertical wall having a plane surface inclined in two directions, first longitudinally inwardly from the tie engaging end of the shoe to the outer end thereof to form a wedge portion extending longitudinally of the shoe behind the slot, and secondly transversely inwardly from the lower edge of the upper edge of the wedge portion; and a steel yoke constructed to span the rail base and provided at one end with a hook for engaging the edge of the rail base remote from the shoe and provided at the opposite end with an upwardly extending portion adapted to engage the transversely and longitudinally inclined wedge portion and yieldingly hold the shoe in gripping engagement with the rail base.

5. A rail anchor comprising a shoe formed of substantially unbendable material having a longitudinal extending slot to embrace an edge of a rail base and formed between non-continuous lower jaws and non-continuous upper jaws, the slot having a substantially vertical wall for contacting the vertical edge of the rail base, the vertical wall having a slight recess formed intermediate its ends so that only the latter contact the adjacent edge of the rail base, the back of the vertical wall having a plane surface inclined in two directions, first longitudinally inwardly from the tie engaging end of the shoe to the outer end thereof to form a wedge portion extending longitudinally of the shoe behind the slot, and secondly transversely inwardly from the lower edge to the upper edge of the wedge portion; and a steel yoke constructed to span the rail base and provided at one end with a hook for engaging the edge of the rail base remote from the shoe and provided at the opposite end with an upwardly extending portion adapted to engage the wedge portion and yieldingly hold the shoe in gripping engagement with the rail base, the outer end of said wedge portion being tapered longitudinally of the shoe in the same direction as the first mentioned longitudinal incline but at a sharper angle to facilitate the engagement of the upwardly extending portion of the yoke with said wedge portion.

6. A rail anchor comprising a shoe formed of substantially unbendable material adapted to engage one edge of a rail base and having a back and a tie abutment, the back having a plane surface provided with a double inclination both being longitudinally inwardly from the said abutment and one forming a longitudinal wedge portion inclined towards the edge of the rail base, the other inclination being at the end of the

wedge portion remote from the abutment and being at a sharper angle than that of the wedge portion, the back also being inclined transversely inwardly from the lower edge to the upper edge thereof; and a yoke of resilient metal adapted to span the rail base and engage the underside thereof, the yoke having a small hook at one end adapted to engage the edge of the rail base remote from the shoe and having an upwardly extending portion at the other end to engage the wedge portion, the said upwardly extending portion being inclined in a direction corresponding to the transverse inclination of the shoe back but at a different angle than that of said transverse inclination so that initially the said upwardly extending portion will engage only along its upper part with the upper edge of the said second mentioned longitudinal inclination.

7. A rail anchor comprising a shoe formed of substantially unbendable material adapted to engage one edge of a rail base and having a back and a tie abutment, the back having a plane surface provided with a double inclination both being longitudinally inwardly from the said abutment, one of said inclinations forming a longitudinal wedge portion inclined towards the edge of the rail base, the other inclination being at the end of the wedge portion remote from the abutment and being at a sharper angle than that of the wedge portion, the back also being inclined transversely inwardly from the lower edge to the upper edge thereof; and a yoke of resilient metal adapted to span the rail base and engage the underside thereof, the yoke having a small hook at one end adapted to engage the edge of the rail base remote from the shoe and having an upwardly extending portion at the other end to engage the wedge portion, the said upwardly extending portion being inclined in a direction corresponding to the transverse inclination of the wedge portion but at a different angle than that of said transverse inclination so that initially the said upwardly extending portion will engage only along its upper part with the upper edge of the said second mentioned longitudinal inclination, the said upwardly extending portion also being initially turned so that its wedge engaging face will lie substantially parallel to the said second mentioned longitudinal inclination remote from the abutment.

8. A rail anchor constructed as set forth in claim 1 in which the upper edge of the upwardly extending yoke portion is substantially flush with the upper edge of the wedge portion.

CHARLES G. ERICSON.
